G. HAMMOND.
MAGAZINE CATCH AND RELEASE.
APPLICATION FILED FEB. 27, 1917.

1,247,528.

Patented Nov. 20, 1917.

UNITED STATES PATENT OFFICE.

GRANT HAMMOND, OF HARTFORD, CONNECTICUT, ASSIGNOR OF ONE-THIRD TO ALVA C. WASHBURNE, OF PITTSFIELD, MASSACHUSETTS, AND ONE-THIRD TO FREDERICK G. CRANE, OF DALTON, MASSACHUSETTS.

MAGAZINE CATCH AND RELEASE.

1,247,528.

Specification of Letters Patent. Patented Nov. 20, 1917.

Application filed February 27, 1917. Serial No. 151,256.

To all whom it may concern:

Be it known that I, GRANT HAMMOND, a citizen of the United States, and a resident of Hartford, in the county of Hartford and State of Connecticut, have invented a new and Improved Magazine Catch and Release, of which the following is a specification.

My invention relates to means for retaining and releasing the magazine of a firearm, and an object of my invention, among others, is to provide a device of this class that shall be extremely simple in its construction, few as to the number of parts, and efficient in operation.

One form of device embodying my invention and in the construction and use of which the objects herein set out, as well as others, may be attained, is illustrated in the accompanying drawings in which:

Figure 1 is a view in side elevation of a firearm embodying my invention, with parts broken away to show construction, and the breech-bolt being shown as located in its rearward position.

Fig. 2 is a top plan view of the handle (the receiver being removed) with the hammer thrown back.

Fig. 3 is a view in side elevation of a portion of a firearm embodying my invention with parts broken away to show construction.

Fig. 4 is a detail view in vertical section through the magazine chamber, the back wall of which is broken away.

Fig. 5 is a detail view of the hammer, sear, and magazine retaining lever, the sear being broken away to show construction.

My invention herein illustrated and described is intended for use in what is commonly known as the "automatic" type of firearm, that is, that type in which upon the pulling of the trigger the firing takes place and is immediately followed by the automatic ejection of the empty cartridge shell and loading of the arm, and with this explanation the following description in connection with the accompanying drawings will be readily understood.

In the said drawings the numeral 10 indicates the handle of a pistol embodying my invention, this handle having a trigger guard 11 within which a trigger 12 is located and which is operatively connected with the other portion of the actuating

mechanism in any suitable manner. A receiver 13 is removably attached to the handle and a barrel 15 is secured to the receiver. The actuating mechanism may be of any approved construction including a hammer 16, a sear 17 and other parts, the construction and operation of which will be readily understood by those skilled in the art and for this reason a general description only is embodied herein.

A magazine 18 is removably located within the handle, this magazine having the usual feed spring 19 acting against a follower 20 upon which the cartridges 21 rest. A retaining notch 22 is formed in the back of the magazine 18 to receive the nose 24 of a retaining lever 23 pivotally mounted in the handle. In the construction herein shown this lever is pivoted intermediate its ends, its lower end having an off-set finger 25 that rests against the side of an actuating plunger 26. This plunger is mounted in a well in the side part of the handle 10, and is seated upon a spring 27 in the bottom of the well, which spring normally forces the plunger upwardly. A retaining lever operating cam 28 formed on the side of the plunger 26 operates against the finger 25 on the retaining lever 23, and the upper end of the plunger engages a recess in the breech-bolt under certain conditions, to be herein-after explained, and holds the breech-bolt in its backward position, as shown herein, a prong 29 being formed on the end of the plunger to engage the breech-bolt at the proper time.

The lever 23 is forced toward the magazine by a spring plunger 30 seated on a spring 31 located in a recess in the sear 17. It will be noted that this arrangement of parts enables a single spring to perform the double function of forcing the sear 17 into position to engage the notches in the hammer 16 and also of forcing the lever 23 to engage the notch in the edge of the magazine.

A holding lever 32 is pivotally mounted in the handle, in the construction herein shown, this lever being supported on a bar 33 secured in an opening through the handle and having a pivot 34 projecting into the magazine chamber. One end of this lever will engage a spring detent 35 in the side of the magazine 18, and its other end

extends into a recess in the side of the plunger 26. The detent 35, when there are one or more cartridges 21 in the magazine, rests against the side of the follower 20, but when the last cartridge has been forced from the magazine and the breech-bolt is not over the follower, the latter will be moved by its spring beyond the end of the detent and the latter, by reason of its spring qualities, will snap inwardly and thus disengage itself from the holding lever 32.

In the operation of the device, a magazine having cartridges therein being in place in the handle will be held by the retaining lever 23. In this position of the parts the lever 32 being in contact with, and held by, the detent 35, each time the pistol is fired the breech-bolt 36 will be forced backwardly and its forward end will pass beyond the prong 29 of the plunger 26, but the latter will be prevented from moving upwardly by the lever 32 and the detent 35, the latter holding said lever.

When the breech-bolt moves forwardly to force the last cartridge from the magazine into the breech in the barrel, the follower 20 will be forced by its spring 19 against the under side of the breech-bolt, where it will rest until the breech-bolt is forced backwardly when the last cartridge is fired. In this backward movement of the breech-bolt caused by the firing of the last cartridge, when the breech-bolt passes backwardly beyond the follower, the latter springs upwardly under the force of its spring 19 releasing the detent 35 that snaps inwardly from underneath the lever 32. Said lever is now held only by the plunger 26, which, as soon as the lever was released by the detent, was forced by the spring 27 so that its prong 29 pressed against the breech-bolt. This position of the parts will exist for an instant only, and during the time that the breech-bolt is traveling backwardly from the position at which it disengaged the follower to the position where its front end passes beyond the prong 29. At this time said prong will spring into the recess in the breech-bolt under the action of the spring 27, and hold it from movement.

In the position of the parts when a magazine is in place in the handle the off-set finger 25 rests in the recess in the plunger 26 partially formed by the cam 28. In the upward movement of the plunger 26 just described, the cam 28 will act against the finger 25 and swing the lever 23 on its pivot, thus disengaging the nose 24 from the notch in the magazine and the latter, being now released, will fall and be discharged from the handle, and this discharging operation may be assisted, if desired, by means of a spring suitably positioned to act upon the magazine for such purpose.

When a loaded magazine is inserted in the

handle the detent 35 will be in position to engage the lever 32, and as the magazine is pushed to place and seated in position the parts herein described will be automatically reset.

In order to manually release the magazine, a knob 40 is attached to a projection extending through a slot in the handle and from the lever 23, movement of said knob operating to release the magazine from the lever 23. In order to manually release the breech-bolt when it is held backwardly by the prong 29, I provide a thumb lever 37 pivotally attached to the outside of the handle and having a lug 38 projecting through the handle and overlying a shoulder 39 at the upper end of the plunger 26. By pressing one end of said thumb lever downwardly the plunger is forced downwardly to move the prong 29 from in front of the breech-bolt and permit the latter to move forward under the force of its spring, the latter being constructed and operating in a manner well known. The lever 32 will not prevent this movement of the plunger 26 for the reason that the movement of the plunger to engage the breech-bolt is so slight that the side of the lever will also always remain against the side of the lug on the detent 35 and at the upper edge of said lug.

In accordance with the provisions of the patent statutes, I have described the principles of operation of my invention, together with the device which I now consider to represent the best embodiment thereof; but I desire to have it understood that the device shown is only illustrative, and that the invention can be carried out by other means.

I claim:

1. A firearm including a frame having a chamber for a magazine, a lever pivotally mounted with one end adapted to project into said chamber to engage and hold the magazine therein, a magazine located in said chamber, an actuating member operatively connected with a movable device on the magazine, and an operative connection between said actuating member and lever to control the operation of the latter.

2. A firearm including a frame having a chamber for a magazine, a lever pivotally mounted with one end adapted to project into said chamber to engage and hold a magazine therein, a magazine located in said chamber, an actuating member operatively connected with a movable device on the magazine, and an operative connection between said actuating member and the opposite end of said lever from that projecting into the magazine chamber, said connection controlling the operation of said lever.

3. A firearm including a frame having a chamber for a magazine, a breech-bolt movably mounted in the frame, a lever pivotally mounted with one end adapted to project

- into said chamber to engage and hold a magazine therein, a magazine located in said chamber, an actuating member operatively connected with a movable device on the 5 magazine, a member movably mounted in the frame to hold the breech-bolt in one position, and an operative connection between said actuating member and breech-bolt holding member to actuate the latter.
- 10 4. A firearm including a frame having a chamber for a magazine, a breech-bolt movably mounted in the frame, a lever pivotally mounted with one end adapted to project into said chamber to engage and hold a magazine therein, a magazine located in said chamber, an actuating member operatively connected with a movable device on the 15 magazine, a member movably mounted in the frame to hold the breech-bolt in one position, an operative connection between said actuating member and the breech-bolt holding member to control the operation of the latter, and an operative connection between the breech-bolt holding member and said 20 lever to control the operation of the latter.
5. A firearm including a frame having a chamber for a magazine, a magazine located in said chamber, an actuating member operatively connected with a movable device 25 on the magazine, a member movably mounted to hold the breech-bolt in one position, and a lever pivotally mounted with one end adapted to project into said chamber to hold a magazine therein and its opposite end engaging said breech-bolt holding member by which it is actuated.
6. A firearm including a frame having a chamber for a magazine and a breech-bolt movably mounted in the frame, an actuating member 30 adapted to be operatively connected with a movable device on a magazine, a member movably mounted to hold the breech-bolt in one position, and a lever pivotally mounted with one end adapted to 35 project into said chamber to hold a magazine therein and its opposite end engaging said breech-bolt holding member by which it is actuated.
7. A firearm including a frame having a 40 magazine chamber therein, a magazine located in said chamber, a pivotally mounted 45
- lever with one end adapted to engage the magazine to hold it in place, a connection between the opposite end of said lever and a movable device on the magazine to control 55 the operations of said lever, a sear pivotally mounted in the frame, a spring located between the sear and retaining lever and exerting force upon both, and a hammer operatively connected with the sear. 60
8. A firearm including a frame having a chamber for a magazine, a lever pivotally mounted with one end adapted to project into said chamber to engage and hold a magazine therein, an actuating member 65 adapted to be operatively connected with a movable device on a magazine, and an operative connection between said actuating member and lever to control the operation of the latter. 70
9. A firearm including a frame having a chamber for a magazine, a lever pivotally mounted with one end adapted to project into said chamber to engage and hold a magazine therein, an actuating member 75 adapted to be operatively connected with a movable device on a magazine, and an operative connection between said actuating member and the opposite end of said lever from that projecting into the magazine 80 chamber, said connection controlling the operation of said lever.
10. A firearm including a frame having a magazine chamber therein and a breech-bolt movably mounted in the frame, a pivotally 85 mounted lever with one end adapted to engage a magazine to hold it in place, a member movably mounted in the frame to hold the breech-bolt in one position and operatively connected with that end of said lever opposite that adapted to engage the 90 magazine, an actuating member adapted to be operatively connected with a movable device on the magazine and also operatively connected with the member for holding the 95 breech-bolt, a sear pivotally mounted in the frame, a spring located between the sear and retaining lever and exerting force upon both, and a hammer operatively connected with the sear.

GRANT HAMMOND.
